RUG WASHING AND DYEING APPARATUS

Gerald W. Pond, Wichita Falls, Tex.

Application April 10, 1934, Serial No. 719,820

2 Claims. (Cl. 8—19)

This invention relates to rug washing and dyeing apparatus and it has particular reference to a dyeing and cleaning vat for rugs and the like, with appurtenances for the convenient handling thereof.

The principal object of the invention is to provide apparatus of the character specified through the medium of which a rug may be cleaned thoroughly and dyed uniformly due to the provision of means by which the rug may be immersed in the dyeing fluid progressively and rolled upon the convenient roller for further handling.

Another object of the invention is to provide means of a simple nature for flushing out the vat preparatory to filling the same with a dye fluid of different color.

Still another object of the invention is to provide for the introduction of steam into the vat for the purpose of heating the fluid and further serves the purpose of bringing about more thorough mixture of the dye with the water or other liquid.

With the foregoing objects as paramount, the invention has particular reference to its salient features of construction and arrangement of parts which will become manifest as the description proceeds, taken in connection with the accompanying drawings, wherein:

Figure 1 is a perspective view of the invention.

Figure 2 is a plan view partly in cross section.

Figure 3 is a vertical section on line 3—3 of Figure 2, and

Figure 4 is a section on line 4—4 on Figure 3.

Continuing with a more detailed description of the drawings, 1 designates an elongated tank or vat for containing water, dyeing fluid or both and which is divided into two or more compartments by a partition 2. Due to this provision, rugs or other articles of various sizes may be washed or dyed without requiring that the tank or vat be entirely filled with fluid. Situated on either side of the tank is a runway or platform 3 and suspended by means of braces 4. These runways provide a convenient walk for an attendant or operator.

Supported upon either end of the tank 1 is a standard 5, the construction of which is better shown in Figure 4. The casting providing these standards is constructed to define inwardly extending webs 6 opposing one another and are adapted to provide tracks or guides for a vertically movable bearing 7, one of which is mounted on each of the standards 5. These bearings are

channeled to slidably receive the webs 6 as apparent in Figure 4.

A chain 8 is connected at one end to an eye 9 provided on each of the bearings 7 and extending over a sprocket wheel 10 journaled in the top of the standard 5 and from the opposite end of the chain 8 is suspended a counterweight 11. Counterweight 11 is likewise channeled to receive a web 12 on the outside of each of the standards 5 and is thus guided in its vertical movements.

Journalized in the bearings 7 is a shaft 13 which carries an elongated drive roller 14, shown only in Figure 1 and which supports the rug during the dyeing operation. The roller has spool ends 15 which prevent the rug from moving off the roller during the operation of dyeing or washing the rug. One end of the shaft 13 extends entirely through one of the bearings 7 and enters a reduction gear box 16, the gears in which are driven by an electric motor 17. Both the motor 17 and the gear box 16 are mounted upon a platform 18 which is integral with or connected to the adjacent bearing 7 in order that it will move therewith.

From the foregoing it is apparent that by operating the crank 19 at the top of each of the standards 5, the sprocket wheel 10 is rotated and the bearings 7 are accordingly moved up and down, carrying with them the shaft 13 upon which is mounted the roller 14, the weight of which and of the motor being counterbalanced by the weight 11. A dog or pawl 20 normally rests between the teeth of the ratchet wheel 10, as apparent in Figure 3 and prevents any undue movement of the sprocket wheel.

Reference to Figures 2 and 3 will disclose a pair of parallel and perforated pipes 21 and 22 extending lengthwise of the vat or tank 1. Pipe 22 affords a medium by which steam is injected into the tank 1 through the valve 23 while the pipe 22 serves to convey dyeing fluid into the tank. A funnel shaped receptacle 24 is provided at the inlet end of pipe 22 for the convenient introduction of dyeing fluid into the tank.

A deflector 25, shown only in Figure 3 is mounted above the pipes 21 and 22 and serves to deflect the incoming dye mixture and steam and is further effective in bringing about a more thorough mixture of the composition.

Water is introduced into the tank through the pipe 26 and perforated pipe 27, its position being such that an even and uniform flow of water may be had throughout the length of the tank 1. A valve 28 controls the water so introduced. A suitable drain 29 is provided beneath the tank to con-

veniently empty the same of its contents and is likewise provided with a control valve 30.

As apparent in Figure 1, a roller 31 mounted upon a shaft or spindle 32 extends alongside and parallel with the tank 1 and is supported by slotted brackets 33 adjacent either end of the tank in order that it may be readily removed after a rug has been washed or dyed and rolled thereupon. Cranks 34 are mounted upon the ends of 10 the shaft 32 for rotating the same.

If it is desired to wash or dye a small rug of a width less than the length of the rollers 13, the partition 2 is arranged in the tank. Otherwise the partition 2 is removed. The rug is immersed 15 in the dye fluid and lifted over the roller 14 and the end of the rug is secured around the roller 31 by revolving the roller 31, the rug is progressively wound thereupon as the process of dyeing progresses. After the entire rug has been wound 20 upon the roller 31, the latter is lifted from its mounting and conveyed to another location for more convenient handling or drying.

Manifestly, the construction shown is capable of considerable modification and such modification 25 as is considered within the scope and meaning of the appended claims is also considered within the spirit and intent of the invention.

What is claimed is:

1. A rug cleaning and dyeing apparatus comprising the combination of a vat of greater length than width, having vertical standards at either end, each of the latter being provided with confronting webs defining a vertical slot, a bearing block disposed in slot of each of said standards

having grooves receiving said webs as guides and capable of movement therebetween, a platform carried by one of said blocks, a motor and gear reducing means on said platform, a sprocket in the top of each of said standards and constrained to rotate in one direction, chains passing over said sprockets and suspending said bearing blocks at one end, a counterbalance carried by the opposite end of each of said chains, a roller disposed above said vat and having its ends journaled in the bearing blocks of said standards whereby to be raised and lowered therewith, means to effect introduction of steam and dye fluid into said vat and a removable roller for receiving the rug from said first roller when the cleaning and dyeing operation is completed. 10

2. A rug cleaning and dyeing apparatus comprising the combination of a vat having standards disposed at either end, each having vertical slots therein opposed by vertical guides, a bearing block retained by said guides in each of said slots, a counter-weight for each of said blocks, a chain overreaching the tops of each of said standards and connecting said blocks and weights, a platform carried by one of said blocks, a motor supported on said platform and movable therewith, a roller having its ends journaled in said blocks whereby to be vertically displaceable relative to said vat, means for introducing water, steam and dyeing fluid into said vat and means to receive rugs from said first roller upon completion of said cleaning and dyeing operation. 20
